GRINDING MACHINE

Ledgeworth G. Casey, Cincinnati, Ohio, assignor
to The Cincinnati Electrical Tool Company,
Cincinnati, Ohio, a corporation of Ohio

Application February 1, 1937, Serial No. 123,328

8 Claims. (Cl. 51—170)

My invention pertains to grinding machines and more particularly to the driving mechanism for the grinding element or grinding wheel of such machines.

Heretofore, it has been difficult to provide a smooth drive to a grinding wheel which was subjected to intermittent cutting operations on a work piece such as is encountered in hand grinding and snagging operations. In such operations there is a tendency for the grinding wheel to momentarily drive the driving motor at the instant the wheel is removed from the work piece because of its usually greater mass and momentum which causes it to be less susceptible to changes in speed than the armature of its driving motor. This lack of conformity of motion of the grinding wheel and driving motor is also encountered when the wheel is running idle, free of any work piece. Particularly is this effect of nonconformity of motion objectionable in grinding machines wherein the transmission connecting the driving motor to the grinding wheel has slack or backlash, such for example as is found in the usual reduction gearing between the motor and the grinding wheel in portable electric hand grinding tools, because of the chatter and vibration set up which tends to destroy the transmission and the accuracy of the grinding operations.

An object of my invention is to provide in a grinding machine, between the driving motor and the grinding wheel, a transmission mechanism wherein the motor may drive the grinding wheel but the grinding wheel may not drive the motor.

Another object is to provide in a grinding machine, a motor and a grinding wheel and a transmission mechanism incorporating an over-running clutch connecting said motor to said grinding wheel whereby the momentum of the grinding wheel can not cause said wheel to drive the motor.

And a further object is to provide in a hand grinder, a motor and grinding wheel and a gear reduction transmission mechanism incorporating an over-running clutch connecting said motor to said grinding wheel.

Other objects of this invention will be understood from the following detailed description of the drawing, in which:

Figure I is a plan view partly in section on line I—I of Figure II showing an exemplary embodiment of my invention in a portable electric hand grinder.

Figure II is a transverse section through the transmission mechanism on line II—II of Figure I.

As an exemplary embodiment I show my in-

vention applied to a portable electric hand grinder comprising the usual electric motor housing 1 and switch handle 2 to which is attached the electric supply cord 3. Connected to the motor housing 1 by suitable screws 4 is the bearing plate 5 and the grinding wheel spindle housing 6. The grinding wheel spindle 7 is journaled in bearing 8, in housing 6 and in bearing 10 in the plate 5. A grinding wheel 11 is appropriately mounted on the wheel spindle 7 by the usual mounting means 12.

The armature shaft 13 of the armature 14 of the motor 15 in the housing 1 is journaled in the bearing 16 in the plate 5 and has a pinion 17 fixed thereon which engages the ring gear 18. 15 Journaled on the bearing portion 19 of the spindle 7 is the cup member 20 which has a hub portion 21 which is journaled in the bearing 22 mounted in the housing 6, thereby providing free rotation of cup 20 on the spindle 7 while at the same time providing an adequate intermediate support for said spindle. The ring gear 18 is fixed on the outside portion of the cup 20 and held in positive driving relation by means of the key 23.

Fixed in driving relation on the spindle 7 is the star wheel 24 by means of key 24a which has the rollers 25 associated therewith in the usual manner for an over-running clutch. A suitable disc 26 also fixed on the spindle 7 adjacent the bearing 10 serves to maintain the rollers 25 in proper axial relation to the star wheel 24 and cup 20.

The over-running clutch comprising the cup 20, the star wheel 24 and associated rollers 25 are 35 so arranged that driving power may be delivered from armature 14 through the pinion 17 and ring gear 18 to drive the spindle 7, but the spindle can not drive the ring gear 18. The result of providing such an arrangement is to cause the 40 ring gear 18 to at all times be driven by the pinion and to prevent the spindle 7 from causing the gear 18 to drive or tend to accelerate the speed of rotation of the motor pinion and armature 14 thus preventing any backlash movement between the pinion 17 and the gear 18 and its inherent chatter and vibration.

Having described my invention, what I claim as new and desire to secure by United States Letters Patent is:

1. In a grinding machine, a frame, a grinding wheel spindle rotatably mounted in said frame, a grinding wheel mounted on said spindle, a motor incorporated in said frame having an armature mounted on an armature shaft rotatably mounted 55

in said frame, a driving pinion on said armature shaft, an over-running clutch mounted on said wheel spindle, and a gear associated with said over-running clutch and engaged by said pinion whereby said motor may drive said grinding wheel and said grinding wheel may not drive said motor.

5 2. In a grinding machine, a frame, a grinding wheel spindle journaled in said frame, a grinding wheel mounted on said spindle, a motor incorporated in said frame having an armature mounted on an armature shaft rotatably mounted in said frame, a driving pinion fixed on said armature shaft, an over-running clutch mounted on said spindle comprising a star wheel fixed to said 10 spindle, a cup journaled on said spindle, and associated rollers, and a ring gear fixed to said cup and adapted to be driven by said pinion whereby said grinding wheel may be driven by said motor and said grinding wheel may not drive 15 said motor.

15 3. In a grinding machine, a frame, a grinding wheel spindle journaled in said frame, a grinding wheel mounted on said spindle, a motor incorporated in said frame having an armature mounted 20 on an armature shaft rotatably mounted in said frame, a driving pinion fixed on said armature shaft, an over-running clutch associated with said spindle comprising a star wheel fixed to said spindle, a cup rotatably mounted on said spindle 25 and in said frame, and associated rollers, and a gear fixed to said cup and adapted to be driven by said pinion whereby said motor may drive said grinding wheel and said grinding wheel may not drive said motor.

30 35 4. In a portable electric hand grinder having wheel spindle, motor, and switch handle portions, a grinding wheel spindle rotatably mounted in said wheel spindle portion, a grinding wheel mounted on said spindle, an armature mounted 40 on an armature shaft rotatably journaled in said motor portion, a pinion fixed on said armature shaft, an over-running clutch associated with said wheel spindle, comprising a star wheel fixed on

5 said spindle, a cup journaled on said spindle, and associated rollers, and a gear fixed on said cup adapted to be driven by said pinion whereby said motor may drive said grinding wheel and said grinding wheel may not drive said motor.

5 5. In a portable electric hand grinder, a frame, a wheel spindle rotatably mounted in said frame, a grinding wheel mounted on said wheel spindle, an electric motor incorporated in said frame, an over-running clutch mounted on said wheel spindle, and means inter-connecting said motor with said clutch whereby said wheel spindle may be rotated by said motor and said motor may not be rotated by said wheel spindle.

10 6. In a grinder, a frame, a wheel spindle rotatably mounted in said frame, a grinding wheel mounted on said wheel spindle, an electric motor incorporated in said frame, an over-running clutch mounted on said wheel spindle, and means inter-connecting said motor with said clutch 15 whereby said wheel spindle may be rotated by said motor and said motor may not be rotated by said wheel spindle.

15 7. In a grinder, a frame, a wheel spindle rotatably mounted in said frame, a grinding wheel 20 mounted in said frame, a grinding wheel mounted on said wheel spindle, an electric motor incorporated in said frame, an over-running clutch mounted on said wheel spindle, and gear-reduction means inter-connecting said motor with said 25 clutch whereby said wheel spindle may be rotated by said motor and said motor may not be rotated by said wheel spindle.

25 8. In a grinder, a frame, a wheel spindle rotatably mounted in said frame, a grinding wheel 30 mounted on said wheel spindle, an electric motor incorporated in said frame, inter-connecting means including an over-running clutch between said motor and said wheel spindle whereby said wheel spindle may be rotated by said motor and 35 said motor may not be rotated by said wheel spindle.

40 LEDGEWORTH G. CASEY.
